Atty's.

UNITED STATES PATENT OFFICE.

WILLIAM L. BEAN, OF CHICAGO, ILLINOIS.

MUD-RING.

1,156,455.

Specification of Letters Patent.

Patented Oct. 12, 1915.

Application filed April 23, 1915. Serial No. 23,278.

To all whom it may concern:

Be it known that I, WILLIAM L. BEAN, a citizen of the United States, and a resident of Chicago, in the county of Cook and State of Illinois, have invented a certain new and useful Improvement in Mud-Rings, of which the following is a description, reference being had to the accompanying drawing, which forms a part of my specification.

10 My invention relates to a mud-ring more especially adapted for use with locomotive fire-boxes, and has for its object the provision of a mud-ring having attenuated portions or surfaces which adapt it to be secured to the walls of the fire-box and to the outside or wrapper-sheet without the use of rivets, thereby obviating the need for rivet-holes being drilled therein and therefore providing a mud-ring having greater 15 strength than the mud-rings as heretofore employed, so that my improved construction is adapted to act as a beam.

Another object of my invention is to provide a mud-ring provided with a channel 20 extending throughout the upper surface thereof and constituting the bottom of the respective water-legs or spaces, adapted for the collection of mud or sediment contained in the water-space of the fire-box; the channel allows the sediment to collect where it will be out of contact with the finished plates which corrode more quickly; finished plates being employed to constitute the comparatively thin walls of the fire-box, the 25 wrapper-sheet, as well as the throat-sheet and back-head. By providing a mud-ring adapted to collect the mud and sediment in the manner specified, the life of the fire-box is enhanced, and the difficulties, heretofore 30 encountered as a result of corrosion in the lower part of the water-legs or water-spaces of the fire-box due to the accumulation of mud and sediment are greatly reduced.

Another object of my invention is to provide a mud-ring whereby the difficulties heretofore encountered, due to leaking and wearing away of the sheets, will be practically eliminated and the frequent repair and renewal of certain portions of the side 35 sheets therefor obviated.

A further object of my invention is to provide a mud-ring, the cost whereof, in manufacture, installation and maintenance, will be materially less than that of constructions heretofore employed.

In the drawing:—Figure 1 is a side eleva-

tion of a locomotive type of fire-box provided with my improved mud-ring. Fig. 2 is a top plan view of the mud-ring. Fig. 3 is a detail cross-sectional view illustrating more clearly the construction of the mud-ring and method of securing the same to the walls of the fire-box and outside or wrapper-sheet.

My invention, as exemplified in the drawing, comprises a mud-ring preferably made of cast steel, provided with the upwardly presented legs or portions 5 and 6. By providing the mud-ring with the extended sides 5 and 6, a channel 7 is formed, which, when the mud-ring is secured in place, 60 constitutes the lower extended portion of the water-legs intermediate of the walls of the fire-box and the wrapper-sheet, the back-head and the throat-sheet.

In the preferred construction of my invention, the mud-ring is also provided with the depending portion or projection 8, which not only stiffens or increases the strength of the mud-ring, but also provides an anchor 65 for the expansion pad between the back-head and the engine-frame as well as for the furnace supports or other parts of the locomotive. The mud-ring, in its preferred 70 form as disclosed in the drawing, presents a 75 construction substantially Y-shape in cross-section; the depending portion or leg 8 being preferably provided throughout the entire mud-ring as shown.

Mud-rings, as heretofore employed, have 80 usually been made solid, of rectangular cross-section, and subsequently provided with holes drilled to receive rivets of comparatively large diameter for the purpose of securing the mud-ring to the fire-box, and 85 to the outside sheets. The process of drilling the mud-ring is not only an expensive one, but also materially affects the strength 90 of the mud-ring. As several rows of rivets are usually provided, generally arranged in 95 a staggered manner, it is evident that a considerable number of holes are drilled, which result in a material weakening of the mud-ring. The present type of construction and manner of securing the mud-ring also results in considerable difficulty being encountered 100 as a result of chipping and calking, especially at the corners where it is impossible to extend all of the rivet holes entirely through the mud-ring, because of the radial 105 manner in which they must be arranged at the corners, so that the use of additional 110

patch-bolts or plugs, extending only part way through the mud-ring, intermediate of the rivets which extend entirely therethrough, has been found necessary. With 5 my improved construction, these difficulties are entirely obviated, because the mud-ring is not intended to be secured to the walls of the fire-box and to the wrapper-sheet by rivets, but is adapted to be secured to the sheet 10 metal walls by means of welding, autogenously or otherwise.

In order to provide a good welding surface, I prefer to bevel the upper surfaces 15 or ends of the legs 5 and 6, as more clearly shown in Fig. 3, where the leg 5, which is intended to be located on the fire-box side, is made with a single bevel as shown at 9, while the leg 6, which is intended to be secured to the outer or wrapper-sheet of the 20 boiler is preferably beveled in the nature of an inverted V, as shown at 10. By beveling the surfaces as shown, a larger welding surface is provided, and the weld or seam will be of such nature as to prevent 25 any possible transverse fracture of the seam. As the wrapper-sheet is usually made of greater thickness than the fire-box side walls, the leg 6 is, therefore, made slightly 30 heavier in cross-section than the leg 5; the legs 5 and 6, in the preferred form, are preferably made to taper slightly, that is, the legs are made of gradually decreasing thickness, so as to somewhat approximate the 35 thickness of the sheets to which they are to be secured.

In the preferred construction, the legs 5 and 6 are made of a length that will produce a channel 7 of a depth substantially equal to its width, thus providing a construction which may be cast without difficulty.

In applying my invention, as shown in the drawing, the leg or portion 6 is first welded on its inner side to the outside or 40 wrapper-sheet 11, thereby producing the weld or seam 12, see Fig. 3, after which the seam or weld may be completed from the outside, as indicated at 13 in Fig. 3.

After the inner seam 12 has been completed, it is evident that the seam or weld, shown at 14, in Fig. 3, may be made, whereby the mud-ring is secured to the fire-box sheet 15.

The length of the upwardly presented 50 portions or legs 5 and 6 are preferably such as to permit a short portion of the fire-box sheets 15 and the wrapper-sheets 11, to extend beneath the first or lowermost horizontal row of stay-bolts, usually employed, 55 as shown at 16, whereby the proper spaced relation of the sheets or walls is maintained.

The depending portion or leg 8 of the transverse or end sections of the mud-ring 60 is provided with holes, as shown in Fig. 3,

at 17; these holes being preferably arranged in staggered relation, as indicated in dotted lines in said figure; the holes permitting the various parts of the locomotive or engine-frame to be secured to the mud-ring. 70 In order to permit the holes to be arranged as described, the depending portion 8 at both ends of the mud-ring are preferably made of increased depth, as shown in Fig. 1.

As the mud and sediment will collect in 75 the channel 7, formed in the mud-ring by reason of the extended or attenuated portions 5 and 6, I prefer to provide the corners of the mud-ring with clean-out ports 18. The ports 18 are preferably arranged, 80 as shown, so that the longitudinal and transverse sections or portions of the mud-ring may be readily cleaned through the same opening. In order that the ports may be suitably closed, the mud-ring is provided 85 with the bosses 19, surrounding the ports, so as to receive suitable threaded plugs, not shown.

It is evident that with my improved construction, the use of rivets for securing the 90 mud-ring to the fire-box and the outside or wrapper-sheet is not only obviated, but the difficulties encountered in driving the rivets,—ordinarily about six inches in length,—and in providing the proper pitch in the 95 wrapper-sheet, throat-sheet and back-head, are entirely eliminated. Furthermore, the use of patch bolts or plugs, adjacent the corners, is also done away with, and, therefore, the source of more or less leaking practically eliminated, as well as the necessity 100 of frequent calking.

My improved mud-ring is preferably made of cast steel, which, owing to its coating of scale, does not corrode as readily as 105 finished plate, although it may be found practicable in some instances to use forged steel.

While I have shown and described what I believe to be the simplest and best form 110 of my invention; it will be understood, however, that the sectional contour of the mud-ring may be altered, and certain other modifications be made without departing from the spirit of my invention, and I do not 115 wish to be understood, therefore, as limiting myself to the exact construction shown and described.

What I claim is:—

1. In combination with a locomotive fire-box and the outside or wrapper sheet, a mud-ring comprising a comparatively thick body, constituting a beam portion, having upwardly presented integral sides to provide a channel, the upper ends of the sides 120 being of a thickness substantially equal to the thickness of the wrapper-sheet and the fire-box walls and welded thereto.

2. A mud-ring for locomotive boilers, comprising a beam forming body-portion 130

- tapering in a downwardly presented flange or leg and in parallel upwardly presented sides, the height of the sides being substantially equal to the distance between the sides 5 so as to provide a channel corresponding in width with that of the water-legs of the boiler, the upper edges of the sides being beveled to provide enlarged welding surfaces.
- 10 3. A mud-ring for the water-legs of locomotive boilers, composed of a beam forming body-portion having upwardly extending sides of different thicknesses to correspond substantially to the thicknesses of the 15 respective walls of the water-legs of the boiler and arranged to be welded thereto.
4. A mud-ring for locomotive-boilers, formed of a single beam forming portion, the upper part whereof is substantially U- 20 shape in cross-section so as to provide a channel corresponding in width with the side water-spaces or legs of the boiler, with the sides of the mud-ring being of thick-
- nesses corresponding substantially to the thicknesses of the respective side walls of 25 said water-spaces or legs and provided with enlarged welding surfaces.
5. A mud-ring for locomotive boilers, formed of a single, beam forming portion provided with a channel substantially of 30 equal height and width, the side walls of the channel being of unequal thickness to correspond with the respective walls of the water-legs or spaces of the boiler.
6. A mud-ring for locomotive boilers, 35 formed of a single, imperforate body-portion, provided with a channel whose side walls are of thicknesses to correspond with the respective walls of the water-legs of the boiler to which they are adapted to be welded, the corners of the mud-ring being provided with clean-out ports.

WILLIAM L. BEAN.
